DOLL PILLOW

Mary W. Peters, Boulder, Colo.

Application October 4, 1954, Serial No. 32,536

Term of patent 14 years

(Cl. D34—2)

Fig. 1.

Fig. 2.

Fig. 3.

Fig. 4.

To all whom it may concern:

Be it known that I, Mary W. Peters, have invented a new, original, and ornamental Design for Doll Pillow, of which the following is a specification, reference being had to the accompanying drawing, forming a part hereof.

I claim:

The ornamental design for a doll pillow, as shown.
